UNITED STATES PATENT OFFICE.

JOHN MORTON AND WILLIAM URIE MORTON, OF GLASGOW, SCOTLAND.

SEWING-MACHINE FOR MAKING EYELETS.

SPECIFICATION forming part of Letters Patent No. 626,815, dated June 13, 1899.

Application filed December 27, 1897. Serial No. 663,631. (No model.)

To all whom it may concern:

Be it known that we, JOHN MORTON and WILLIAM URIE MORTON, sewing-machine manufacturers, of Bothwell Circus, Glasgow, in the county of Lanark, Scotland, have invented certain new and useful Improvements 5 in Sewing-Machines, (which have been patented in Great Britain by Letters Patent, dated August 15, 1891, No. 13,775,) of which the following is a specification.

The invention relates to machinery for sewing rings or gromets into sails, tarpaulins, awnings, tents, wagon-covers, horse-clothing, and other coverings, the machine being also 15 applicable for making eyeholes—*i. e.*, edges holes—without using a ring or gromet.

The invention is illustrated by the accompanying drawings.

Figure 1 is a side elevation, partly in section, of a machine embodying the invention; and Fig. 2, a front elevation of part of the same. Fig. 3 is a sectional view of the needle-bar tube with its internal gear; Fig. 4, a plan of the clamping device, and Fig. 5 a sectional view showing the needle-plate.

1 represents the machine-bed.

2 is the arm; 4, the needle-shaft; 5, the cam on needle-shaft which operates the toothed wheel 6 on the vertical shaft 7, and 8 is the 30 spur-wheel at the lower end of said shaft.

The cam 5 may be described as a worm having a single ridge 3 on its circumference, and as the needle-shaft 4 brings this part around it turns the toothed wheel 6 the distance of 35 one tooth. The spur-wheel 8 causes the parallel vertical shaft 9 to revolve by engaging with the spur-wheel 10.

11 and 12 are bevel-gears at the upper and lower ends of the shaft 9. The horizontal 40 shaft 13 passes through the machine-arm and obtains motion from bevel-gear 11 through the medium of an exactly similar gear 14. On the opposite end of the horizontal shaft 13 is another bevel-gear 15, which turns the needle-bar tube 16 by engaging with the bevel-gear 17.

The horizontal shaft 18, which passes under the machine-bed, has at its right-hand end bevel-gear 19, which obtains motion from the 50 bevel-gear 12. On the left-hand end of the shaft 18 there is a bevel-gear 20, which en-

gages with another gear 21, fixed to shuttle-shaft 22.

On the needle-shaft 4 there is an eccentric 23, whose connecting-rod 24 is coupled to one 55 end of a rocking lever 25, the other end of this rocking lever being forked and fitted with rollers which fit into a grooved collar 26. The collar 26 encircles the shuttle-shaft 22 and, being loose on said shaft, allows the shaft to 60 revolve within it. The grooved collar 26 rises and falls in obedience to the rocking lever 25 and carries with it a link 27, which connects said collar to a bell-crank 28. The long arm of said bell-crank is marked 29 and forms the 65 shuttle-lever, the shuttle-carrier 30 being fixed thereto. The upper end of the shuttle-shaft 22 is flattened, as at 60, and on this is carried the stud 61, on which the bell-crank oscillates. To the flat part of the shuttle-shaft 60 there is also fixed a circular plate 62, and as the shuttle-shaft 22 revolves it is kept 70 from swaying by rollers 63, of which there are four, bearing at equal distances on the circular plate 62. The rollers 63 are sustained by a 75 bracket 64, which is bolted to the machine-bed 1. It will thus be clear that the shuttle-lever 29 reciprocates as the eccentric 23 moves around with the needle-shaft 4 and that as the shuttle-shaft 22 is revolved the path of the 80 shuttle-lever 29 must always be in a line which constitutes a diameter of the circular plate.

The needle-bar tube, with its connections, is detailed at Fig. 3. The needle-bar tube 16 is raised and lowered by a heart-shaped cam 85 fixed to a block 32, which clasps the needle-bar tube and carries it up and down, this arrangement being a well-known device used in raising and lowering the needle-bar in ordinary sewing-machines. The block 32 is an 90 iron casting having a hole bored perpendicularly through it to allow the needle-bar tube 16 to revolve within it, and the block 32 raises and lowers the needle-bar tube by acting on collars 65 and 66, which are fixed to the needle-bar tube and revolve with it. A double-grooved cam 37, secured on the front end of the needle-shaft 4, acts as a disk as well as a cam, having on its face a stud carrying a roller, said roller working in the heart-shaped 95 cam to carry the block 32 and the needle-bar tube 16 up and down as the needle-shaft 4

rotates. The needle-bar or cross-head 31, to which the needle is attached, moves transversely of the needle-bar tube 16 in a slot therein, as shown particularly at Fig. 3, being retained in the slot by a plate 33', secured to the bottom of the tube 16, the bar or cross-head 31 having an inclined slot 34.

35 is a bar which passes within the needle-bar tube 16 and lower end of said bar being furnished with a stud which works in the inclined slot 34 in the cross-head 31 and the upper end being provided with a pin which is acted on in the manner hereinafter described, so that as said bar rises and falls the needle 36 is alternately thrown out and in, so as to take one stitch inside and the next outside the gromet or eyehole, as shown particularly at Fig. 5. The bar 35 is caused to move up and down by means of the double-grooved cam 37, fixed on the needle-shaft 4. The double-grooved cam 37 may be described as a cylinder with two circumferential grooves cut in it and having a fixed switch at one point of its circumference, so that the gib 25 which is attached to a bar 38, being pointed and following in the aforesaid grooves, is moved alternately from one groove to the other as the needle-shaft 4 revolves. The bar 38 is supported by brackets 59, pivoted 30 at 67, and as the gib before mentioned follows to either groove of the double-grooved cam 37 the bar 38 imparts motion to the lower arm of a bell-crank lever 39, the other arm of the bell-crank being forked to embrace and 35 impart motion to a grooved collar 40, which surrounds the needle-bar tube 16. This collar 40 receives in a recess on its inner surface the pin of the bar 35, which pin extends through a slot 68 in the metal tube 16. When 40 the collar 40 is moved up and down by the action of the bell-crank lever 39, the bar 35 is caused to act on the inclined slot 34 of the cross-head 31 and traverse this needle to the outer and inner side of the gromet or eyehole.

The needle-bar tube, as shown at Fig. 3, allows free passage for the thread at 45, and thus prevents twisting.

The take-up lever 46 is fastened to the needle-bar tube 16 and is connected by a link 47 to a grooved collar 48, which encircles the needle-bar tube and revolves with it, but is kept from moving up and down with it by the arms 49.

55 The clamp device consists of a ring 50, hinged at its periphery to the forked end of a vertical rod 52, guided on the machine-arm at 51, and this rod is raised when a gromet or eyehole has been sewed by one end of a 60 double-ended lever 58, the other end of this lever being acted upon by a cam-piece 59, actuated by a handle 70, the clamp being normally held upon the cloth by the action of a spring 57. The ring 50 can be turned out of 65 the way transversely of the machine after being raised by means of a handle 53 upon

the vertical rod 52. The ring 50 may be provided with teeth or spikes on its under side in order to keep the cloth from turning. As shown at Figs. 4 and 5, the ring 50 has a 70 flange on which rests the flat circular plate 54', kept from rising by the catches 55 and turned with the shuttle-shaft 22 by means of a projecting part 71 of the needle-plate 56 passing through it.

75 The rotating needle-plate (shown at Fig. 5) is constructed as follows: 56 is the needle-plate, which is made circular and screwed to the top of the shuttle-race 57, said race being fixed to the shuttle-shaft 22. By preference 80 the needle-plate 56 is formed with a recess 72, in which the ring or gromet lies; but it may be used without, and in making eyeholes no recess is necessary.

Having now described the invention, what 85 we claim, and desire to secure by Letters Patent, is—

1. In combination the rotary needle-bar tube with means for reciprocating it vertically, means for rotating the bar-tube, said needle-bar tube having but a single needle connected thereto eccentrically thereof, to describe a circle as the bar is turned, a shuttle, means for supporting and rotating the same continuously in one direction, means for oscillating the shuttle as it is being rotated and the gearing between the shuttle-rotating means and the needle-bar-tube-rotating means, substantially as described.

2. In combination, the needle-bar tube with means for reciprocating and turning the same, a single needle arranged eccentric to the needle-bar tube, the shuttle, a rocking lever pivoted at its lower end carrying the same directly at its upper end, a rotary part carrying 105 the rocking lever, a collar adapted to slide on the rotary part and connected with the rocking lever, means for moving the collar and means for turning the rotary part, substantially as described.

3. In combination, a needle-bar tube, a cross-head for carrying the needle carried in a groove cut transversely of the axial line of said tube, a bar for operating the cross-head carried inside the needle-bar tube, a sleeve 115 for actuating the same surrounding the needle-bar tube, a shuttle and means for rotating and oscillating the same substantially as described.

4. In combination, the needle-bar tube, a 120 needle carried thereby, the bar 31 at the lower end thereof having a groove and movable laterally in relation to the tube, the bar 35 having a pin operating in the groove of the bar 31 for operating the needle with means for operating the bar 35, and the shuttle mechanism with means for operating the same substantially as described.

5. In combination in a machine for sewing rings or gromets into sails and the like, a 130 needle-bar tube, means for reciprocating the same, a take-up lever fixed to the needle-bar,

a collar encircling the needle-bar tube and rotating with it, the link connecting the collar and take-up and means for holding the collar against movement vertically with the 5 needle-bar, substantially as described.

6. In combination, the shuttle-shaft, the plate 57 connected therewith, the needle-plate 56 connected with the plate 57, the shuttle, the clamp-plate 50, the plate 54 carried by 10 the plate 50 and rotating with the needle-

plate, the needle and means for operating the same substantially as described.

Signed at Glasgow, in the county of Lanark, Scotland, this 10th day of December, 1897.

JOHN MORTON.
WM. URIE MORTON.
